UNITED STATES PATENT OFFICE.

VOLNEY STEPP, OF MANHATTAN, KANSAS.

TRACE-CARRIER.

SPECIFICATION forming part of Letters Patent No. 241,441, dated May 10, 1881.

Application filed March 25, 1881. (Model.)

To all whom it may concern:

Be it known that I, VOLNEY STEPP, of Manhattan, in the county of Riley and State of Kansas, have invented a new and Improved 5 Trace-Carrier, of which the following is a specification.

The object of my invention is the production of a cheap, durable, and efficient trace-holder for harnesses, one which will hold the cockeyes 10 in any position of the harness, and one with which the cockeyes may be engaged and disengaged without trouble.

In the accompanying drawings, Figure 1 is 15 a top view of my invention, and Figs. 2 and 3 are, respectively, side and front elevations of the same.

Similar letters of reference indicate corresponding parts.

The device is preferably of cast-iron or similar metal, and the bottom plate, *a*, thereof is 20 convex in form to fit the back of the horse, and is provided with the slots *b b* for the hip-strap of the harness, and with the front slot, *c*, for the back-strap, and with the cross-piece *d* for the crupper. Rising from the bottom plate are the undercut horns *e e*, over which the cockeyes *f f* are placed. Above the horns *e e* are 25 the upwardly-curved keepers *g g*, which reach from the rear of the bottom plate over and be-

yond the horns, and are supported by the 30 bridge *h*, which rises from the center of the forward part of the bottom plate.

The under sides of the keepers *g g* are formed with the projections *i i*, which are in such position relative to the horns *e e* that the cockeyes cannot be disengaged from the horns except by proper manipulation.

To engage and disengage the cockeyes with the horns the end of the trace must be brought to nearly a horizontal position and the cock-eye turned so as to pass edgewise between the horns and the projections *i i*. This being a position which the traces never assume of their own accord, it follows that the traces hooked upon the carrier are always secure against 45 casual unhooking of the cockeyes.

Having thus fully described my invention, I claim as new and desire to secure by Letters Patent—

The trace-carrier herein shown and described, consisting of the bottom plate, *a*, having the undercut horns *e e*, in combination with the keepers *g g*, having the projections *i i*, substantially as and for the purposes set forth.

VOLNEY STEPP.
